UNITED STATES PATENT OFFICE.

DONALD F. WHITING, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

1,327,185.

Specification of Letters Patent. Patented Jan. 6, 1920.

Application filed December 28, 1918. Serial No. 268,756.

To all whom it may concern:

Be it known that I, DONALD F. WHITING, a citizen of the United States, residing at New York, in the county of Bronx, State 5 of New York, have invented certain new and useful Improvements in Telephone Systems, of which the following is a full, clear, concise, and exact description.

This invention relates to telephone systems and more particularly to such systems employing long transmission lines over which both telephonic and signaling currents may be transmitted.

In such systems the signaling current required for operating the signal control apparatus associated with the switchboard ends of the transmission line is usually of low frequency and is not suitable for transmission over long transmission lines. It is 15 customary, therefore, to associate with the line apparatus which is responsive to low frequency signaling currents transmitted from the switchboard end of the line for connecting higher frequency signaling currents with the line for transmission thereover. Apparatus responsive to the higher frequency signaling currents is also provided intermediate the ends of the line for connecting with the switchboard end low 25 frequency signaling currents suitable for operating the signaling apparatus located at the switchboard.

The object of this invention is to provide improved signaling means for systems of 30 this character.

In attaining the object of the present invention, therefore, the apparatus responsive to signaling currents transmitted over the line may be associated therewith through an 40 amplifier whose connection with the line is through means resonant to the signaling currents transmitted over the line.

For a more complete understanding of this invention, reference should be had to the 45 following description, considered in connection with the accompanying drawing, which illustrates the invention embodied in a four-wire transmission system of which only so much is shown as is necessary for a proper 50 understanding of the present invention. A complete four-wire transmission system, with which the arrangements of the present in-

vention may be associated, is shown in the application of John F. Toomey, Serial No. 196,897, filed October 16, 1917.

As shown in the drawings, the four-wire transmission system comprises, a circuit L_1 incoming to a junction station, a circuit L_2 outgoing from the junction station, and a terminating circuit L_3 extending from the junction station to terminating apparatus (not shown) at a switchboard. The terminating circuit L_3 is associated with the outgoing circuit L_2 through a repeating coil comprising primary windings 5, 5 and secondary windings 6, 6. The incoming circuit L_1 is connected with the terminating circuit L_3 through the windings of an auto-transformer 7, bridged across the mid-points of the primary windings 5, 5 of the repeating coil. The incoming circuit L_1 and the terminating circuit L_3 are of different impedances, and the auto-transformer 7 serves to minimize reflection losses resulting from the transmission of telephonic currents from the incoming circuit L_1 to the terminating circuit L_3 . For the purpose of balancing the terminating circuit L_3 with respect to currents incoming over the incoming circuit L_1 , there is provided an artificial balancing line 80 L_4 connected in circuit with the primary windings 5, 5 of the repeating coil.

In order that signaling current of the proper frequency (approximately 133 cycle) for propagation over the transmission line 85 may be connected with the outgoing circuit L_2 when low frequency signaling current (approximately 16 cycle) is impressed upon the terminating circuit L_3 at the switchboard end thereof, there is provided at the junction station a ringing response relay 8 connected in series with a condenser 9 and in bridge of the terminating circuit L_3 . For proper balancing, the relay 8 and its associated condenser 9 are connected across the mid-points of the primary windings 5, 5 of the repeating coil. This ringing response relay 8 responds to 16 cycle signaling current, and through a slow release relay 10 controls the connection of 133 cycle signaling current with the outgoing circuit L_2 .

In order that low frequency signaling current for operating signal control apparatus at the switchboard may be connected

with the terminating circuit L_3 when the higher frequency signaling current is transmitted over the incoming circuit L_1 , there is provided at the junction station a relay 11 responsive to 133 cycle signaling current incoming over the circuit L_1 . This relay 11 controls through a slow-operating and slow releasing relay 12 and a ringing relay 13, the connection of 16 cycle signaling current with the terminating circuit L_3 . The relay 11 is connected in the output circuit of an amplifier 14, whose input circuit is connected in series with the secondary winding of an input repeating coil 15. The primary winding of this input coil 15 is connected in parallel with a condenser 17. This condenser 17 is connected between the middle windings of the auto-transformer 7 and serves to provide a path of low impedance to talking currents. The condenser 17 is also of higher impedance to signaling current of 133 cycles and coöperates with the primary winding of the input coil 15 to form a closed circuit resonant to signaling current 133 cycles. Therefore, when 133 cycle signaling current is impressed across the terminals of the condenser 17, local oscillatory currents are set up in the closed resonating circuit. These local oscillatory currents, which are of much greater magnitude than the currents incoming over the line section L_1 , in flowing through the primary winding of the input coil 15, induce potentials in the secondary winding of this coil. These induced potentials are impressed upon the input electrodes of the amplifier 14. Due to these oscillatory currents of great magnitude, the closed resonating circuit offers an effective impedance to signaling currents of 133 cycles commensurate with the impedance offered to these currents by the auto-transformer and the incoming line section L_1 , thereby minimizing the effect of the impedance of the auto-transformer to such currents. Condensers 22 and 23, through which the auto-transformer 7 is connected with the mid-points of the primary windings, are of such capacity as to present a very high impedance to signaling currents but a very low impedance to talking currents. It will be understood, therefore, that the shunt path about the ringing response relay 8 is of high impedance to signaling currents to which this relay is responsive. A condenser 18 provided in series with the windings of the relay 11, prevents the flow of direct current therethrough and coöperates with the inductance of the relay to tune the output circuit to 133 cycle signaling current.

If talking currents be transmitted from the switchboard end of the terminating circuit L_3 these currents are induced through the windings of a repeating coil into the outgoing circuit L_2 , while talking currents transmitted over the incoming circuit L_1

traverse the windings of the auto-transformer 7 and are induced into the terminating circuit L_3 .

If signaling current of 133 cycles be transmitted to the junction station over the incoming circuit L_1 , these impulses are repeated through the windings of the input coil 15 into the input circuit of the amplifier 14, which amplifies them and transmits them into the output circuit in which the relay 11 is connected. The relay 11 thereupon responds to such amplified signaling current incoming over the incoming circuit L_1 , and opens the normally closed energizing circuit of the relay 12. This relay, in releasing its armature, completes an energizing circuit causing the operation of ringing relay 13. The operation of this ringing relay 13 connects the source of signaling current 20 with the terminating circuit L_3 .

Low frequency signaling current incoming to the junction station over the terminating circuit L_3 from the switchboard end thereof causes the operation of ringing response relay 8, this relay, through the co-operation of the associated condenser 9, being tuned to respond to signaling currents of this frequency. The operation of this ringing response relay 8, causes the operation of the slow release ringing relay 10, which connects the source of signaling current 21 with the outgoing circuit L_2 . The operation of this relay 10 also closes a contact which is in multiple with the normally closed contact of the relay 11. This is to insure that relay 12 will not release should the ringing response relay 11 accidentally respond to the 16 cycle signaling current incoming to the junction station over the terminating circuit L_3 .

While the present invention has been shown in connection with the terminating end of a four-wire transmission system, it will be apparent that it is equally applicable to a two-wire system in which signaling currents of one frequency are transmitted over one line section for operating switching apparatus, which connects signaling current of another character with the succeeding line section.

What is claimed is:

1. In a telephone system, in combination, a transmission line, an amplifier for amplifying signaling currents transmitted over one section of the line, a parallel circuit comprising a condenser and an impedance resonant to signaling current connecting the amplifier with the one line section, a separate source of signaling current, and a relay responsive to amplified signaling currents for controlling the connection of the separate source with another section of the line.
2. In a telephone system, in combination, a transmission line, an amplifier for amplifying signaling currents transmitted over

- one section of the line, a closed circuit resonant to such signaling currents and comprising a condenser and an impedance connected in bridge of the one section for associating therewith the amplifier, a separate source of signaling current, and a relay responsive to amplified signaling currents for controlling the connection of the separate source with another section of the line.
5. In a telephone system, in combination, a transmission line, an amplifier for amplifying signaling currents transmitted over one section of the line, a condenser connected with the transmission line, a transformer having its primary winding connected in a closed circuit with the condenser and its secondary winding connected with the amplifier, a separate source of signaling current, and a relay responsive to amplified signaling currents for controlling the connection of the separate source with another section of the line.
10. 3. In a telephone system, in combination, a transmission line, an amplifier for amplifying signaling currents transmitted over one section of the line, a condenser connected with the transmission line, a transformer having its primary winding connected in a closed circuit with the condenser and its secondary winding connected with the amplifier, a separate source of signaling current, and a relay responsive to amplified signaling currents for controlling the connection of the separate source with another section of the line.
15. 4. In a telephone system, in combination, a transmission line, an amplifier for amplifying signaling currents transmitted over one section of the line, a condenser, a transformer having its primary winding associated with the condenser to form a closed circuit and connected in bridge of the one line section and resonant to signaling currents transmitted thereover, the secondary winding being connected with the amplifier, a separate source of signaling current, and a relay responsive to amplified signaling current for controlling the connection of the separate source with another section of the line.
20. 5. In a telephone system, in combination, two sections of a transmission line of different impedances over which talking and signaling currents are transmitted, means joining the sections for minimizing reflection losses resulting from the transmission of talking currents from one section to the other, an amplifier for amplifying signaling currents transmitted over one line section, means resonant to signaling current coöperating with the reflection loss minimizing means for associating the amplifier with the one line section, a separate source of signaling current, and a relay responsive to amplified signaling currents for controlling the connection of the separate source with the second line section.
25. 6. In a telephone system, in combination, two sections of a transmission line of different impedances over which talking and signaling currents are transmitted, an autotransformer joining the line sections for minimizing reflection losses resulting from the transmission of talking currents from one line section to the other, an amplifier for amplifying signaling currents transmitted over one line section, means comprising a condenser and impedance resonant to signal-
- ing current coöperating with the autotransformer for associating the amplifier with the one line section, a separate source of signaling current and a relay responsive to amplified signaling current for controlling the connection of the separate source with the second line section.
30. 7. In a telephone system, in combination, two sections of a transmission line of different impedances over which talking and signaling currents are transmitted, an autotransformer joining the sections for minimizing reflection losses resulting from the transmission of talking current from one section to the other, an amplifier for amplifying signaling currents of one character transmitted over one line section, a condenser connected between the windings of the autotransformer, a repeating coil having a primary winding connected in a closed circuit with the condenser and its secondary winding connected with the amplifier, a separate source of signaling current, and a relay responsive to amplified signaling current for controlling the connection of the separate source with the second line section.
35. 8. In a telephone system, in combination, two sections of a transmission line of different impedances over which talking and signaling currents are transmitted, means joining the sections for minimizing reflection losses resulting from the transmission of talking currents from one section to the other, an electroresponsive device responsive to signaling current transmitted over one line section, means resonant to signaling current coöperating with the reflection loss minimizing means for associating the electroresponsive device with the one line section, a separate source of signaling current, and a switching relay operating upon the response of the electroresponsive device to connect the separate source with the other line section.
40. 9. In a telephone system, in combination, two sections of a transmission line of different impedances over which talking and signaling currents are transmitted, an autotransformer joining the sections for minimizing reflection losses resulting from the transmission of talking currents from one section to the other, a condenser connected between the windings of the autotransformer, an electroresponsive device responsive to signaling current transmitted over one line section, a transformer having its primary winding associated with the condenser to form a closed circuit resonant to the signaling currents transmitted over the one line section and having its secondary winding associated with the electroresponsive device, and a separate source of signaling current connected with the other line section upon the response of the electroresponsive device.
45. 10. In a telephone system, in combination,

two sections of a transmission line of different impedances over which talking and signaling currents are transmitted, means joining the sections for minimizing reflection losses resulting from the transmission of talking currents from one section to the other, an electroresponsive device responsive to signaling current of one character transmitted over one line section for controlling the connection of signaling current of a dif-

ferent character with the other line section, and means resonant to signaling current transmitted over the one line section and coöoperating with the reflection loss minimizing means for associating the electroresponsive device with the one line section. 15

In witness whereof I hereunto subscribe my name this 27th day of December, A. D. 1918.

DONALD F. WHITING.
